UNITED STATES PATENT OFFICE.

FRANK G. CALDWELL, OF WHEELING, WEST VIRGINIA.

DESIGN FOR A CEILING OR WALL PANEL.

SPECIFICATION forming part of Design No. 25,330, dated March 31, 1896.

Application filed February 19, 1896. Serial No. 579,971. Term of patent 14 years.

To all whom it may concern:

Be it known that I, FRANK G. CALDWELL, a citizen of the United States, residing at Wheeling, in the county of Ohio and State of West Virginia, have invented or produced a new and original Design for Ceiling and Wall Panels, of which the following is a specification.

This design has for its object to provide a novel sheet-metal ceiling or wall panel which presents a handsome and characteristic appearance to the eye.

The leading feature of the design consists in a square or rectilineal figure having four equal sides and four right angles and an intaglio face provided with a centerpiece, at each side of which is a set of rectilineal crossing-moldings.

The design is illustrated by the accompanying drawings, in which—

20 Figure 1 is a plan view looking at the ornamental face of the panel; and Fig. 2 is a sectional view taken on the line 2 2, Fig. 1.

25 In the drawings, illustrating my new and original design, the numeral 1 indicates the body of the sheet-metal ceiling or wall panel. This body comprises a square or rectilineal

figure having four equal sides 2, 3, 4, and 5 and four right angles. The panel is formed with an intaglio face having a centerpiece 6, at each side of which is a set of rectilineal 30 moldings 7, 8, 9, and 10. The sets of moldings inscribe the centerpiece 6, and across each set of moldings extend a plurality of corrugations or stripes 12, by which the intaglio face of the panel appears as having a large 35 number of bulbous protuberances. The centerpiece is also ornamented with crossing corrugations or stripes.

The design provides an ornamental sheet-metal ceiling or wall panel which presents a 40 distinguishing appearance and possesses characteristic features of configuration.

What I claim is—

The design for a sheet-metal ceiling or wall panel, substantially as shown.

45 In testimony whereof I have hereunto set my hand in presence of two subscribing witnesses.

FRANK G. CALDWELL.
